[57] CLAIM

The ornamental design for an air flow deflector, substantially as shown and described.

DESCRIPTION

FIG. 1 is a perspective view taken from the front, bottom and one side of an air flow deflector showing my new design;

FIG. 2 is another perspective view taken from the top and side shown in FIG. 1;

FIG. 3 is a top plan view thereof;

FIG. 4 is a rear elevational view thereof;

FIG. 5 is a front elevational view thereof;

FIG. 6 is a bottom plan view thereof;

FIG. 7 is a left end elevational view thereof; and

FIG. 8 is a right end elevational view thereof.
